ELECTRIC SWITCH

Daniel Rönnberg, Ludvika, Sweden, assignor to
 Allmänna Svenska Elektriska Aktiebolaget,
 Västeras, Sweden

Application January 12, 1933, Serial No. 651,279
 In Sweden January 23, 1932

12 Claims. (Cl. 200—150)

The present invention relates to such circuit breakers where the arc of rupture is extinguished by a flow of fluid for instance oil or water or a suitable gas. The invention relates further to 5 such circuit breaker, where the flow of fluid is caused by the arc itself.

In previous constructions of breakers of this kind a flow of the extinguishing fluid has either been accomplished by an auxiliary arc or by a 10 plunger operated by the switching mechanism.

When an auxiliary arc is used for the above mentioned purpose, the breaker usually becomes rather complicated and the use of an auxiliary arc is combined with severe disadvantages 15 especially at closing the breaker chiefly due to electrodynamical action.

In the use of a special plunger, driven from the mechanism, the chief disadvantage is that the driving mechanism in all cases at every interruption must cause the same flow of fluid regardless of the magnitude of the current to be interrupted. As the force necessary to cause 20 a flow sufficient to extinguish a short circuit arc is very great, the driving mechanism in this form of breakers has always a considerable load.

Other breakers are also known where a flow of extinguishing fluid is caused by the arc itself, but in these breakers the vapor developed by 30 the arc acts immediately on the extinguishing fluid which by the pressure of the vapor is pressed in a stream across the path of the arc. In these breakers, the arc therefore must get a rather considerable length before the extinguishing action can take place.

According to the present invention, the flow of fluid is caused by a plunger mechanism driven by the arc itself. The power available for the plunger mechanism is therefore automatically increased with the current to be interrupted.

According to the invention the contacts of the breaker are enclosed in a chamber which is connected with another chamber by one or a plurality of channels of which one may be traversed by the arc.

The present invention is disclosed in the accompanying drawings in which: Fig. 1 is a section showing one form of the circuit breaker; Fig. 2 is a detail sectional view drawn to a larger scale and showing part of the breaker; Figs. 3 to 13 inclusive are views, corresponding to Fig. 2, but showing various modified forms; Fig. 14 is a view drawn partly in section and showing another form of the circuit breaker; Fig. 15 is an enlarged detail view showing in section part of

the breaker of Fig. 14; Figs. 16 to 18 inclusive are similar views but showing slightly modified forms; Fig. 19 is a sectional plan view of Fig. 18; and Figs. 20 and 21 are sectional views showing two other forms of the circuit breaker. 5

Referring to Fig. 1, an oil vessel 1 is closed by a cover 2. This cover is provided with leading through insulators 3 which are extended into the vessel and supports the stationary contacts 8 and the extinguishing chambers 4. 5 is an insulating rod supporting the movable contacts 6, which are fastened to the rod by means of a bridge 7.

The extinguishing chambers are shown in an enlarged scale in Fig. 2. In this figure, 8 is the stationary contact supported by the insulator 3. 15 The contact 8 is provided with shallow contact blocks 9 forming a sleeve contact and supported by the leaf springs 10 and pressed together by the annular formed spiral springs 11. The contact 8 is surrounded by a metal sleeve 12, which 20 supports the cylinder 13 by means of the collar 16, which is connected to the sleeve 12 by four spaced radially extending arms or spokes extending between the collar 16 and the said sleeve 12. This cylinder 13 is made of a suitable in- 25 sulating material for instance bakelized paper and provided with a cover 14 and bottom 15. The cover 14 and bottom 15 are held apart by rods 17 and provided with holes 18 and 19 for the passage of the movable contact 6. The hole 30 18 in the cover 14 has nearly the same diameter as the movable contact 6, but the hole 19 in the bottom 15 is considerably greater than the contact. Beneath the bottom 15 a floating cover 20 with a close fitting hole 21 is arranged. Due to 35 the floating arrangement of the cover, the hole can be very close fitting the contact regardless of the movable contact not being in accurate alignment with the axis of the cylinder 13. Surrounding the cylinder 13 a metal cylinder 22 is 40 arranged, which is provided with a metal collar 23 at its upper end and a bent over edge 24 at its lower end, which close fits the cylinder 13. The collar 23 is close fitting the metal sleeve 12 45 and is at its inner diameter provided with an annular groove 25. The groove 25 communicates with the extinguishing chamber by openings 29 and with the space outside the chamber by means of the opening 30. The openings 29 are normally 50 closed by valves 28 pressed against the holes by means of helical springs 27.

The device acts in the following manner. When the movable contact 6 separates from the stationary contact blocks 9, an arc between the 55

contacts appears, which heats the fluid firstly in the upper chamber 32 and then in the lower chamber 33. Due to the pressure arising in the chambers an upward force acts on the lower side of the collar 23 and a downward force on the bent over edge 24 of the cylinder 22. The former force is materially greater than the latter, so that the resulting force will give the cylinder 22 a motion in upward direction. By this motion the space between the cylinders 22 and 13 decreases and the upper chamber 32 increases, so that fluid is pressed from the first space into the space 33 through holes 31 in the walls of the insulating cylinder 13 and from there through the hole 18 into the chamber 32. After extinction of the arc, the cylinder 22 is brought back by the helical spring 34 or by its own weight.

The valves 29 are arranged in order to prevent a dangerous pressure to arise in the chambers, and are dimensioned only to open at an excessive pressure. In order to facilitate the departure of gases from the space between the cylinders the collar 16 is provided with small holes 35.

In Fig. 3, the stationary contact is integral with a cylinder 36 which is fastened to the insulator 3. The cylinder 36 is provided with a piston 37 that by means of rods 38 is connected to another piston 39 movable in a second cylinder 40. This may preferably be made of an insulating material and has a diameter materially minor to that of the cylinder 36. When the movable contact 41 separates from the stationary contact, an arc appears between this contact and the stationary contact 42, and as both cylinders are filled with an insulating fluid, this will evaporate and cause a pressure acting upwardly on the piston 37 and downwardly on the piston 39. Due to the difference in piston area the pistons will move upwardly. At this motion the fluid in the smaller cylinder will be pressed through the hole 43 and thereby extinguish the arc. After extinguishing the arc, the pistons are pressed back by the spring 44.

In Fig. 4, 36 is a metal cylinder fastened to the insulator 3. Said cylinder is provided with a piston 37 which by means of rods 38 is connected to another piston 39, movable in a second cylinder 40. This may preferably be made of insulating material and has a diameter materially minor to that of the cylinder 36. The movable contact consists of a rod and is designated by 41. The stationary contact 42 is yieldably mounted and electrically connected to the metal cylinder 36.

The cylinders 36 and 40 are separated by a stationary insulating wall 45 and provided with a hole or channel 43, traversed by the movable contact. When the movable contact 41 separates from the stationary contact an arc appears between this contact and the stationary contact 42, and as both cylinders are filled with an insulating fluid, this will evaporate and cause a pressure acting upwardly on the piston 37 and downwardly on the piston 39. Due to the difference in piston-area the pistons will move upwardly. At this motion the fluid in the smaller cylinder is forced through the hole or channel 43, thereby extinguishing the arc. After the arc has been extinguished the pistons are forced back to the original position by means of the spring 44.

In Figs. 5 and 6 forms are shown where the cylinders are movable in relation to each other. Corresponding parts are designated by the same figures as in the preceding figure. The upper cylinder may in this case also preferably be of

metal and the lower cylinder of some insulating material. The stationary contact is also in this case yieldably mounted and an insulating wall 45 is also arranged between the cylinders. Said insulating wall is supported by rods 46 and the piston 37 with the cylinder 40 is forced back to the original position by means of helical springs 47 surrounding the rods 46. The lower cylinder 40 is rigidly fastened to the piston 37 so that when a pressure arises in the cylinders due to the arc of rupture, the piston 37 moves upwards and with it the cylinder 40 with the bottom 39. The space between the wall 45 and the bottom 39 is then reduced so that a flow of liquid is forced from said space through the channel 43 into the upper cylinder. In the form shown at Fig. 5 the liquid also passes through the channel 49 and openings 50 in the stationary contact.

Figs. 7, 8 and 9 show modifications where the insulating wall 45 is replaced by a series of walls 52 provided with holes forming a longitudinal channel for the arc between the contacts. In Fig. 7 these walls 52 are arranged a small distance from each other and so also in Fig. 8, but in Fig. 8 the walls are provided with further holes 53 arranged on opposite sides, so that a flow of fluid across the arc is obtained. In Fig. 9 a section of the arrangement according to Fig. 8 perpendicular to the section in Fig. 8 is shown.

In Fig. 10 the stationary contact 54 is arranged on a movable plunger 55 that is movable in the cylinder 56. This cylinder is fastened on the insulator 57 and the stationary contact is connected to the cylinder 56 by means of a flexible conductor 58. A spring 59 tends to hold the plunger 55 in its lower position. The plunger 55 is provided with an insulating cylinder 60 and a collar 62. Inside the cylinder 60, a wall 61 is arranged a small distance from the stationary contact 54 and provided with a channel traversed by the movable contact 41. The cylinder 56 is provided with a cylinder of insulating material 63, that surrounds the cylinder 60. Inside the cylinder 63 the collar 62 of the plunger 55 fits rather well. The bottom 64 of the cylinder 63 is also provided with a channel for the movable contact, and in the plunger 55 a hole 67 is arranged.

The arrangement acts in the following way: When the contact 41 separates from the stationary contact 54, an arc appears between the contacts and causes a violent evaporation of the fluid surrounding the contacts. The pressure generated thereby acts downwardly on the upper side of the piston or plunger 55 and upwardly on the lower side of said plunger and its collar or flange 62. Due to the larger area of the lower surface of the piston 55 it is forced upwards so that the liquid inside the cylinder 56 is compressed. At this compression a powerful flow of liquid is forced through the hole 67 and through the hole in the insulating wall 61 into the space on the lower side of the plunger 55, i. e., into the space enclosed by the flange 62, the wall 61, the cylinder 63 and the bottom 64. As the arc also traverses the hole or channel in the wall 61 it is brought into a very intimate contact with said flow of liquid and is therefore rapidly extinguished.

The arrangement according to Fig. 11 differs from that of Fig. 10 only in that the stationary contact with the plunger 55 is fixed to the insulator 57 by means of a rod 65. In this arrangement the cylinder 56 with the cylinder 63 is mov-

able and is held in its upper position by means of the spring 59.

When the arc appears a pressure arises in the chamber enclosed between the plunger 55 and the bottom 64, and said pressure is also transmitted through the channel 67 in the plunger 55 into the space enclosed by said plunger and the cylinder 56. Due to this pressure an upwardly directed force acts on the top of the cylinder 56 and a downwardly directed force on the bottom 64 of the cylinder 63. As the area of said bottom is larger than the top of the cylinder 56, a resulting force, downwardly directed, will act on the cylinder 63 and force it downwards. The space enclosed by the cylinder 56 and the plunger 55 is thereby reduced and a flow of liquid is forced through the channel in the wall 61.

In Fig. 12 the stationary contact 54 is attached to the metal part 66, which also supports the insulating cylinders 70 and 73. The cylinder 70 is provided with a wall 71 beneath the stationary contact and the cylinder 73 is provided with the bottom 74. The space on opposite sides of the cylinder 70 communicates by means of holes 68 in the cylinder 70. Between the cylinders 70 and 73 a metal cylinder 72 is movable. This cylinder is provided with a collar at its lower part with a diameter equal to the inner diameter of the cylinder 73. In this modification the insulating cylinders are stationary and only the metal cylinder movable and held in its lower position by means of the springs 69 which are held in position by means of rods 75.

The action of the arrangement is the following:

The pressure arising at the appearance of the arc acts downwards on the upper surface of said cylinder. As the part of the cylinder 72, which moves in the annular-formed groove in the metal part 66 has a materially smaller sectional area than the area of the lower side of the cylinder 72 with its flange, the cylinder is forced upwards and the space enclosed by said cylinder and said groove is therefore reduced and liquid forced through the channel in the insulating wall 71 into the space on its lower side.

The arrangement according to Fig. 13 is similar to that of Fig. 12. The insulator 57 supports a metal cylinder 86 that in its turn supports an insulating cylinder 80 provided with a wall 81 beneath the stationary contact. The outer cylinder 83 is movable and may also be provided with an inner metal cylinder 85. The cylinder 83 is held in its upper position by means of the springs 69 held in position by means of the rods 75. The cylinder 83 is also provided with a bottom 84 provided with a hole traversed by the movable contact 41. The metal cylinder 86 is provided with holes 88 for the extinguishing fluid. The cylinder 80 is fastened to the cylinder 82 that also supports the rods 75.

The function of the device is the following:

The pressure generated by the arc acts downwardly on the bottom 84 and upwardly on the lower surface of the inwardly directed collar of the metal cylinder 85. As the downwardly directed force is materially greater, the cylinder 83 with the metal cylinder 85 and its collar moves downwards whereby the inner rim of said collar slides against the outer side of the metal cylinder 86. At this motion the space between the cylinders 85 and 86 is reduced and a flow of liquid is forced through the holes or channels 88 into the space inside the cylinder 86 and from there through the channel in the insulating wall 81.

In Fig. 14 a form of the invention is shown, which is especially suitable when water is used as an extinguishing fluid. In this figure, 91 are the insulators supporting the stationary contacts 97, which are surrounded by a plurality of cylinders forming an extinguishing chamber. The movable contacts 93 are arranged on a bridge 94 supported by an insulating rod 95 connected with the operating mechanism not shown on the drawings. The insulators 91 may be supported by a beam 92 of suitable material. The extinguishing chamber is shown in detail in Fig. 15.

In this figure, the stationary contact 97 is arranged in the bottom of a vessel formed by the cylinder 104, which is provided with a bottom 15 and with a cover 105. This cylinder may be made of a suitable metal and so also the other cylinders surrounding the contacts if only the covers are made of an insulating material. The stationary contact is yieldably supported by the metal cylinder 107 with which it is connected by means of springs 110, bolts 109 and flexible conductors 108. The cylinder 98 is supported by means of pillars 106 fastened at the bottom of the vessel. Close to the cylinder 98 a movable cylinder 102 with bottom 101 is arranged and this latter cylinder is rigidly connected to the cylinder 100 movable in the vessel 104. The cylinder 99 is provided with a cover 99, so that the stationary contact is entirely enclosed. The movable contact moves through a hole in the cover 99, and the cylinder 100 is also provided with a cover 103 which acts as piston. Corresponding to the hole in the cover 99 the covers 103 and 105 are also provided with holes for the movable contact. The movable contact 93 has a central bore at its lower part and this bore communicates with the space outside by means of longitudinal channels 96.

This arrangement acts in the following manner: When the contacts separate, an arc appears between the contacts, and a vaporization of the water takes place. In the first moment steam will pass the channels 96 so that the pressure on either side of the cover 99 viz. the bottom 101 will be nearly equal. The pressure on the lower sides of the cover 103 will cause an upward motion of the cylinder 100 and as the cylinder 102 is rigidly connected to the cylinder 100, a contraction of the space inside the cylinder 98 takes place. Due to this contraction a flow of extinguishing fluid is pressed through the hole in the cover 99 and causes a rapid extinguishing of the arc. Usually the breaker is filled with water up to the line marked by the arrow but less water can also be used.

In Figs. 16 and 17, two modifications of the arrangement according to Fig. 15 are shown. In Fig. 16 the stationary contact 111 is provided with a hole and also the cylinder 112 with a channel 113, so that in this modification the movable contact need not be hollow. At breaking, the steam will escape through the channel 113 to the space outside the cylinder 98. The modification according to Fig. 17 differs from that of Fig. 16 only in that the stationary contact is a sleeve contact with sprung contact blocks 116.

Fig. 18 shows another modification of the form shown in Fig. 15, but in the modification according to Fig. 18 the path of the arc is crossed by a plurality of channels 119 formed by the disks 118 which are shown in plan in Fig. 19.

In the form shown in Figs. 14-18, a valve 117 is provided to avoid excess pressure to arise inside the cylinder next to the contacts.

In Fig. 20, a form of the invention is shown where two pairs of contacts are enclosed in one cylinder. In Fig. 20, 121 are the stationary contacts which are supported by the insulators 122 which are fastened in the cover 123 of the breaker. By the insulators 122 a cover 124 is supported and this cover is connected with a cylinder 126 made of a suitable insulating material. This cylinder is closed at its lower end by a movable bottom 127 which is connected to the movable cylinder 128 which surrounds the inner cylinder 126. The cylinder 128 is at its upper end closed by a cover 129, which is provided with holes for the insulators 122, so that the cylinder 128 with cover 129 and bottom 127 can move up and down. The space between the cylinder 126 and the bottom 127 as well as the space between the insulators 122 and cover 129 is made as small as possible to avoid oil leakage.

20 The space enclosed by the cylinder 126, cover 124 and bottom 127 communicates with the space outside the cylinder 126 by channels 132 in the cylinder 126 close to the arcs.

At breaking the arcs formed between the stationary contacts 121 and movable contacts 133 cause a pressure that is transmitted through the openings 132, so that a pressure will act on the lower side of the cover 129. On the bottom 127 the pressure on both sides will be equal but act in opposite directions. The cylinder 128, cover 129 and bottom 127 will therefore move upwards and cause a contraction of the space enclosing the contacts. Due to this contraction the fluid enclosed in this space is pressed through the openings 132 and will then come in intimate contact with the arcs.

In Fig. 21 another form of the invention is shown where also two stationary contacts are enclosed in the same space. The stationary contacts are surrounded by a cylinder 136 of insulating material. Around this cylinder another cylinder 138 is arranged, which may be made of metal. This latter cylinder is provided with a collar 137 which closely fits the inner cylinder 136. The cylinder 138 is further provided with a collar 139 at its upper end, which is movable in an annular space 140 formed by the annular parts 134 and 144. This space communicates by small channels 141 with the atmosphere. The cylinder 138 with its collar 139 is held in its lower position by means of springs 135.

When the pressure caused by the arcs acts on the collar 139, the cylinder 138 moves upwardly and thereby the space between the cylinder 136 and 138 is contracted, so that the fluid contained in that space is pressed through the openings 142 into the space in the cylinder 136 and comes then in intimate contact with the arcs.

I claim as my invention:

60 1. An electric circuit breaker comprising stationary contacts, movable contacts engaging said stationary contacts, a chamber enclosing the contact point between cooperating stationary and movable contacts, a chamber adjacent to said chamber, a differential piston forming parts of the walls of said chambers and actuated by the pressure generated by the arc of rupture, a channel spaced from said contact point and forming the principal communication between said chambers, said channel being opened by the movable contact during the rupturing motion, and being traversed by fluid displayed by said piston.

75 2. An electric circuit breaker comprising stationary contacts, movable contacts engaging

said stationary contacts, a chamber enclosing the contact point between cooperating stationary and movable contacts, a chamber adjacent to said chamber, a differential piston forming parts of the walls of said chambers and actuated by the pressure generated by the arc of rupture, a channel forming the principal communication between said chambers, said channel being traversed by a flow of fluid forced forward by action of said differential piston and by the arc of 10 rupture.

3. An electric circuit breaker comprising stationary contacts, movable contacts engaging said stationary contacts, a chamber enclosing the contact point between cooperating stationary and movable contacts, a chamber adjacent to said chamber, a differential piston forming parts of the walls of said chambers and actuated by the pressure generated by the arc of rupture, a plurality of channels forming the principal 20 communication between said chambers and traversed by a flow of fluid, one of said channels being traversed also by the arc.

4. An electric circuit breaker comprising stationary contacts, movable contacts engaging said stationary contacts, a chamber enclosing the contact point between each pair of cooperating stationary and movable contacts, a chamber adjacent to said chamber, a differential piston forming parts of the walls of said chambers and actuated by the pressure generated by the arc of rupture, a channel forming the principal communication between said chambers, said channel being traversed by the movable contact, by the arc of rupture, and by a flow of fluid from one 35 chamber to the other.

5. An electric circuit breaker comprising stationary contacts, movable contacts engaging said stationary contacts, concentrical cylinders movable in relation to each other, annular and disc 40 formed parts connected to said cylinders and forming with the said cylinders for each pair of contacts two chambers with different cross section, a differential piston comprising parts of the walls of said chambers rigidly connected to 45 together and movable in said chambers, a channel connecting said chambers and traversed by the movable contact, by the arc of rupture, and by a flow of extinguishing fluid forced forward by said differential piston.

50 6. An electric circuit breaker comprising stationary contacts, movable contacts engaging said stationary contacts, concentrical cylinders movable in relation to each other, annular and disc 55 formed parts connected to said cylinders and forming with the said cylinders for each two engaging contacts two chambers with different cross section, a differential piston comprising parts of the walls of said chambers rigidly connected together and movable in said chambers, a 60 stationary wall of insulating material placed at a small distance from the stationary contact and separating the two chambers, a channel in said wall traversed by the movable contact, by the arc of rupture and by a flow of fluid from one chamber to the other.

7. An electric circuit breaker comprising stationary contacts, movable contacts engaging said stationary contacts, concentrical cylinders movable in relation to each other, annular and disc 70 formed parts connected to said cylinders and— together with the said cylinders—forming, for each two engaging contacts, two chambers with different cross section, a differential piston comprising parts of the walls of said chambers rigidly connected to 75

- gether and movable in said chambers, a stationary wall of insulating material placed at a small distance from the stationary contact and separating the two chambers, a channel in said 5 wall traversed by the movable contact, by the arc of rupture, and by a flow of fluid from one chamber to the other, a floating disc closing one of said chambers, and a channel in said disc traversed by the movable contact and tightly fitting to it.
10. An electric circuit breaker comprising containers partly filled with an extinguishing liquid, stationary contacts arranged beneath the surface of said liquid, movable contacts engaging said stationary contacts, a differential pressure device comprising, concentrical cylinders movable in relation to each other, and disc shaped parts connected to said cylinders and forming chambers enclosing said contacts, a channel 15 connecting said chambers and traversed by a flow of liquid from one chamber to the other in contact with the arc of rupture between the contacts.
15. An electric circuit breaker comprising a plurality of stationary contacts, a plurality of movable contacts engaging said stationary contacts, a cylinder surrounding said contacts, a movable bottom for said cylinder, a container enclosing said contacts, a piston rigidly connected to said movable bottom and movable in 20 said container, and channels in immediate proximity to the point of engagement of said contacts.
20. An electric circuit breaker comprising stationary contacts, movable contacts engaging said stationary contacts, two chambers changeable in volume and enclosing said stationary and movable contacts, means for changing the volume of said chambers in opposite senses by the action 25
- of the arc of rupture, a stationary wall separating said chambers and arranged in front of said stationary contact, a channel in said wall traversed by the movable contact and arc of rupture, one or a plurality of valves closing channels between said chambers and the space outside the chambers, said valves preventing an excess pressure in the chambers.
25. An electric circuit breaker comprising a container partly filled with an extinguishing liquid, a stationary contact arranged beneath the surface of said liquid, a movable contact engaging said stationary contact, a stationary cylinder surrounding said stationary contact, a stationary cover in said cylinder arranged in front of said stationary contact, a channel in said cover traversed by said movable contact, a movable cylinder arranged outside said stationary cylinder, a bottom part and a cover fixed to said cylinder, each closing a chamber formed by 30 said cylinders and enclosing said contacts.
30. An electric circuit breaker comprising a plurality of containers partly filled with an extinguishing liquid, a stationary contact in each container arranged beneath the surface of said liquid, a movable contact engaging said stationary contact, a stationary cylinder surrounding said stationary contact, a stationary cover in said cylinder arranged in front of said stationary contact, a channel in said cover traversed by said movable contact, a movable cylinder arranged outside said stationary cylinder, a bottom part and a cover fixed to said movable cylinder, each closing a chamber formed by 35 said cylinders and enclosing said contacts, a plurality of valves arranged in the walls of said chambers in order to prevent excess pressure inside the chambers.

DANIEL RÖNNEBERG.
